[57] CLAIM

The ornamental design of a wall block, substantially as shown and described.

DESCRIPTION

FIG. 1 is a perspective view of a first embodiment of the wall block showing my new design;

FIG. 2 is a top view thereof;

FIG. 3 is a bottom view thereof;

FIG. 4 is a front view thereof;

FIG. 5 is a rear view thereof;

FIG. 6 is a sectional view taken along the line 6—6 of FIG. 2;

FIG. 7 is a sectional view taken along the line 7—7 of FIG. 3;

FIG. 8 is a second modification of the wall block of my new design;

FIG. 9 is a top view of FIG. 8;

FIG. 10 is a bottom view of FIG. 8;

FIG. 11 is a front view of FIG. 8;

FIG. 12 is a rear view of FIG. 8;

FIG. 13 is a sectional view taken along the line 13—13 of FIG. 9;

FIG. 14 is a sectional view taken along the line 14—14 of FIG. 10;

FIG. 15 is a perspective view of a third embodiment of the wall block of my new design;

FIG. 16 is a top view of FIG. 15;

FIG. 17 is a bottom view of FIG. 15;

FIG. 18 is a front view of FIG. 15;

FIG. 19 is a rear view of FIG. 15;

FIG. 20 is a sectional view taken along the line 20—20 of FIG. 16;

FIG. 21 is a sectional view taken along the line 21—21 of FIG. 17;

FIG. 22 is a perspective view of a fourth embodiment of the wall block of my new design;

(List continued on next page.)

FIG. 23 is a top view of FIG. 22;
FIG. 24 is a bottom view of FIG. 22;
FIG. 25 is a front view of FIG. 22;
FIG. 26 is a rear view of FIG. 22;
FIG. 27 is a sectional view taken along the line 27—27
of FIG. 23;

FIG. 28 is a sectional view taken along the line 28—28
of FIG. 24;
FIG. 29 is a perspective view of a fifth embodiment of
the wall block of my new design;
FIG. 30 is a top view of FIG. 29;
FIG. 31 is a bottom view of FIG. 29;
FIG. 32 is a front view of FIG. 29;
